DISTRIBUTOR HEAD FOR STOKERS

William C. Peyton, New York, N. Y., assignor to
The Standard Stoker Company, Incorporated,
a corporation of Delaware

Application July 24, 1931, Serial No. 552,867

4 Claims. (Cl. 110—101)

This invention relates to distributor heads for use with stokers of the scatter feed type, and more particularly to that type of distributor head wherein the portion thereof which contains the pressure fluid jet openings is formed as a member separable from the main body of the distributor head.

It is the object of this invention to construct a sectional distributor head which is cheaply manufactured, readily installed and cheaply maintained and in which a tight joint between its component parts is obtained to prevent leakage of pressure fluid.

More specifically, the invention resides in certain details of construction which function to produce an improved distributor head as will appear in the following description when read in connection with the accompanying drawings, in which

Fig. 1 is a vertical longitudinal section of a portion of a locomotive and a stoker therefor, showing the invention in position therein;

Fig. 2 is a plan section on the line 2—2 of Fig. 1;

Fig. 3 is a section on the line 3—3 of Fig. 1 looking in the direction of the arrows;

Fig. 4 is an enlarged view of a portion of the sectional distributor head as shown in Fig. 3; and

Fig. 5 is a section taken on the line 5—5 of Fig. 4.

Referring now to the drawings, the numeral 10 designates a locomotive having a backhead 11 provided with a firing opening 12. A suitable stoker is provided for supplying fuel to the locomotive. The stoker comprises a riser conduit 13 which constitutes the forward section of a series of connected conduits leading from a suitable source of fuel supply such as the fuel bin of the locomotive tender (not shown).

The riser conduit 13 extends upwardly and is curved forwardly for delivering fuel to the opening 12 onto a distributor plate 14 and is provided with a movable cover section 15 hinged at its upper end as at 16, whereby access may be had to the interior of the riser conduit for the purpose of inspection and repairs.

Suitable means for distributing the fuel over the firebox is provided which includes a novel sectional distributor head 17 arranged to issue a fan-shaped blast of pressure fluid over the distributor plate 14. This plate comprises a flat central portion 19 and a pair of outwardly curving pockets or depressions 20, 20a and the J-shaped deflecting ribs 21, 21a which serve to intercept a portion of the fuel as it is swept over the distributor plate by the blast of pressure fluid issuing from said distributor head, in this manner supplying fuel to the rear corners of the firebox.

The distributor plate 14 is detachably secured to the upright wall 22 of the riser conduit and fits snugly into a recess 23 therein, said plate

forming an extended floor portion of said conduit.

Immediately rearward of the distributor plate 14 and vertically disposed in the upright wall 22 of the conduit 13 is the novel sectional distributor head 17 mentioned herebefore and which will now be more fully described. The sectional distributor head comprises a main body portion 24 and a top or hood member 25. The main body portion 24 is preferably a flat, hollow, plate-like member provided with a top wall 26, a bottom wall 27, the end walls 28, 28a and the side walls 29, 29a. Included between these walls are the several steam chambers such as 30 which are separated by the partition walls such as 31. Each of the steam chambers 30 has its bottom wall 27 threaded as 32 to receive a suitable pressure fluid supply line 32a.

The top wall 26 of the main body portion 24 is provided with a series of vertically drilled passages 33 which are recessed or counter-drilled concentrically at their uppermost portions to form seats such as 34. The drilled passages 33 communicate with the steam chambers 30 and also with passages in the hood member 25 as will presently appear.

The top or hood member 25 comprises a flat front face 35, a curved roof 36 and a base portion 37 provided with aligned downwardly extending projections or nipples 38 which correspond in number to the number of seats 34 of the main body portion and which are spaced similar to the spacing of the seats 34. Each of the projections 38 is arranged to snugly fit in one of said seats. Drilled vertically into the hood member 25 and coaxial with the projections 38, are the passages 39. Since the drilled passages 33 and 39 are coaxial with the recesses or seats 34 and the projections 38 respectively, these passages will be in absolute register with each other when the hood member 25 is interfitted with the main body portion 24, thereby forming a series of continuous passages from the steam chambers 30 to the hood member 25. Gaskets 40, preferably of copper, are placed between the contacting surfaces of the seats 34 and the projections 38 to insure tight connections therebetween. The projections or nipples 38 of the hood member are of greater length than the depth of the seats 34 in the main body portion which insures the said projections or nipples to be seated tightly against the gaskets 40 in the seats 34 without permitting the base portion of said hood member to contact the top wall of said main body portion.

Jet openings 41 pass through the front face 35 of the hood member 25 in a manner to communicate with the drilled passages. These jet openings are in horizontal alignment and when the hood member is in proper relation with the main body portion 24, are adapted to direct blasts of pressure fluid across the upper surface of the dis-

tributor plate 14 for projecting the fuel to all parts of the firebox as rapidly as it is delivered onto the distributor plate.

Extending outwardly from the end walls 28, 5 28a of the main body portion 24, are the flange members 42, 42a which are arranged to pass over the stud members 43, 43a respectively threaded into the upright wall 22 of the riser conduit 13. Suitable nuts are threaded over the stud members 43, 43a respectively to secure the main body portion 24 with said riser conduit 13.

The top wall 26 of said main body portion 24 is threaded as at 44, 44a to receive the stud members 45, 45a respectively and the uppermost side 15 of said riser conduit upright wall 22 is threaded to receive the stud members 46, 46a. The hood member 25 is provided with the laterally extending flanges 47, 47a which are drilled as at 48, 48a to pass over the stud members 46, 46a respectively. The central portion of said hood member is also drilled as at 49, 49a in a manner to pass over the stud members 45, 45a respectively. Suitable nuts are threaded over these stud members to secure the hood member 25 to the main body portion 24, thereby causing the gaskets 40 to be compressed between the interfitted members 34 and 38 to insure tight joints therebetween.

By arranging my novel sectional distributor head so as to provide a separate gasket for each 30 jet passage, the gaskets may be made relatively small and more easily and cheaply manufactured than if only one gasket for the entire sectional distributor head were used. These smaller gaskets consequently have a smaller area exposed 35 to the cutting action of the steam, thereby prolonging the life of the same with respect to that of one large gasket, as well as maintaining a tight joint between the interfitted members for a greater length of time.

40 I claim:

1. A pressure fluid distributor head comprising a hollow plate-like body member and a hood member, said body member being provided with bottom, top, side and end walls, a plurality of chambers in said body member including partition walls separating said chambers extending between said bottom and top walls, said top wall being provided with a series of passages communicating with said chambers, each passage being of less cross-sectional area than that of the chamber with which it communicates said hood member being provided with a series of passages extending upwardly therein and having jet openings communicating with and arranged at substantially right angles with said passages therein, said first and second named series of passages being arranged to be in register with each other so as to form a series of continuous passages, the adjacent faces of said body member and said hood member being provided with means whereby said adjacent faces may be interfitted with each other to provide a joint for each of said passages, the aforesaid means including nipples on the adjacent face of one of said members and seats in the adjacent face of the other member receiving the nipples, and means for securing said hood member to said body member.

2. A sectional distributor head arranged to issue pressure fluid, comprising a hollow plate-like body member and a hood member having a base portion, a flat front face, an arcuate roof and

5 rear portion and end walls, a plurality of nipples on said base portion, said hood member being provided with passages drilled upward therein through and co-axial with said nipples, said flat front face of said hood member being provided with a plurality of horizontally spaced jet openings, each of said jet openings communicating with a respective passage, a lug extending from each of said end walls, said hood member and said lugs being apertured to receive means 10 for securing said hood member to said plate-like body member, said body member being provided with bottom, top, side and end walls, a plurality of chambers in said body member including partition walls separating said chambers extending 15 between said bottom and top walls, said top wall being provided with a series of passages communicating with said chambers, each of the last-named passages being of less cross-sectional area than that of the chamber with which it communicates, 20 said top wall having a recess formed therein concentric with and circumscribing the upper portion of each of said last-named passages to form seats, each of said seats arranged to receive one of said nipples whereby the adjacent faces of said 25 body member and said hood member can be interfitted to align said first and second named series of passages to form a series of continuous passages and provide a joint for each of the last-named passages.

3. As a new article of manufacture, a pressure fluid receiving section of a sectional distributor member of a stoker comprising when in operative position bottom, top, side and end walls arranged in substantial rectangular conformation, a plurality of chambers in said body member including partition walls separating said chambers extending between said bottom and top walls, the top wall of said receiving section being provided with passages extending therethrough and communicating with said chambers, each passage being of less cross-sectional area than that of the chamber with which it communicates, a plurality of such passages communicating with each of said chambers, said top wall 35 having recesses formed therein coaxial with and circumscribing the upper portion of each of said passages to form seats in said top wall, and the bottom wall of said receiving section being provided with a plurality of passages, each passage 40 communicating with a respective chamber.

4. As a new article of manufacture, a discharge section of a sectional pressure fluid distributor head comprising a flat front face, a flat base substantially at right angles thereto, an arcuate roof joining the remote edges of said front face and said base, said discharge section in cross section taken perpendicular to said base and front face being substantially quarter round, a row of nipples extending downwardly from said base, said discharge section being provided with passages 55 extending upwardly through said base coaxially with said nipples and terminating short of said arcuate roof, each passage extending through a respective nipple and being of less cross sectional area than said nipple, the front face of said 60 discharge section having discharge orifices disposed at approximate right angles to said passages, each opening at one end into one of said 65 passages.
